Edgar Dale & Co.

UNITED STATES PATENT OFFICE..

HENRY A. LEMAY, OF BROOKLYN, NEW YORK.

SPLICING-MACHINE.

1,345,375.

Specification of Letters Patent. Patented July 6, 1920.

Application filed December 9, 1919. Serial No. 343,484.

To all whom it may concern:

Be it known that I, HENRY A. LEMAY, a citizen of the United States, and residing at Brooklyn, in the county of Kings and State 5 of New York, have invented certain new and useful Improvements in Splicing-Machines, of which the following is a specification, such as will enable those skilled in the art to which it appertains to make and 10 use the same.

This invention relates to machines or apparatus for splicing thread, cord, rope or the like, and the object of the invention is to provide a machine or apparatus which will 15 quickly and easily splice threads, cords or the like, and in such a manner as to securely bind the separate parts of the thread or cord together and to accomplish this result without materially increasing the size or 20 transverse dimensions of the thread or cord; a further object of the invention is to provide a machine or apparatus of the class and for the purpose specified which may be held in the hand and operated by hand to 25 produce the desired result thus permitting of the use of the apparatus at any place without interfering with other machines or machinery in connection with which the thread or cord is employed, or in the manu- 30 facture of such thread or cord; and with these and other objects in view the invention consists in a machine or apparatus for the purpose specified which is simple in construction and operation and efficient in use. 35

The invention is fully disclosed in the following specification, of which the accompanying drawing forms a part, in which the separate parts of my improvement are designated by suitable reference characters 40 in each of the views, and in which:

Figure 1 is a transverse section through my improved splicing machine with part of the construction shown in elevation and showing the parts in their normal and inoperative position;

Fig. 2 a partial section on the line 2—2 of Fig. 1 indicating the method of connecting threads, cords or the like with the machine;

Fig. 3 a plan view of the construction as shown in Fig. 2;

Fig. 4 a partial section on the line 4—4 of Fig. 2;

Fig. 5 a partial section on the line 5—5

of Fig. 3 and showing the parts in their 55 operative position; and,

Fig. 6 a detail view diagrammatically illustrating a thread or cord spliced by my improved machine or apparatus.

In practice, I provide a box-shaped frame 60 10 comprising side walls 11, end walls 12 and 13 and a bottom 14, the frame 10 is open at the top as shown at 15. The bottom of the frame is provided approximately 65 centrally thereof with a downwardly directed handle member 16.

Passed centrally and longitudinally through the frame 10 is a shaft 17, which has a bearing in the end walls 12 and 13. Secured to the shaft 17 inwardly of the wall 70 12 is a large gear 18 inwardly of which is a pinion 19, and secured to the shaft 17 inwardly of the wall 13 is a large gear 20 which corresponds in size to the gear 18.

For the purpose of description I will call 75 my improved machine a thread splicing machine, or a machine constructed for the purpose of splicing threads either in the manufacture of thread, or in the use of threads in manufacturing fabrics, garments or parts 80 of garments. The top central portion of each of the end walls 12 and 13 are recessed to receive thread holding members 21 and 22. The thread holding member 21 consists of an outer disk 23, and an inner pinion 24 85 joined by a pin 25. The member 21, or the separate parts thereof, are provided with a radial and approximately V-shaped slot 26 which passes to the central axis of the pin 25 and into which a thread or one end portion 90 of a thread 27 is adapted to be placed, the free end of said thread being secured in a V-shaped notch 28 in the end wall 13, as is illustrated in Fig. 3 of the drawing.

The thread holding member 22 consists 95 of an outer disk 29 and inner pinion 30 joined by a pin 31. The member 22, or the separate parts thereof, are provided with a radial and approximately V-shaped slot 32 similar to the slot 26 and which is adapted 100 to receive one end portion of another thread 33 to be spliced with the thread 27, the free end of the thread 33 being connected with a V-shaped notch 34 in the end wall 12 as clearly shown in Fig. 3.

Secured to the end wall 13 is a pin 35 upon which a pinion 36 is mounted, said pinion meshing with the gear 20 and with

the pinion 30 on the member 22, as clearly shown in Fig. 1. The pinion 24 on the member 21 meshes directly with the gear 18. With this gear construction, it will be seen that the threads 27 and 33 in the operation of the machine will be unwound in opposite directions, as hereinafter described.

Mounted longitudinally and centrally of the bottom portion of the frame 10 is another shaft 37, the ends of which have bearings in the end walls 12 and 13. Mounted on the shaft 37 are two brush carrying members 38 and 39, each of which consists of cross head portions 40 in which suitable brushes 41 are mounted, and said members are provided at their ends with downwardly directed arms 42 having enlarged bearings 43 at their lower ends through which the shaft 37 passes. The bearings 43 of the member 39 are arranged inwardly of the bearings on the members 38, as will be seen on a consideration of Figs. 1, 2, 3 and 5 of the drawing. The cross heads 40 of the members 38-39 are provided with downwardly directed plates 44 with which spiral springs 45 are connected, said springs being also connected with the side walls 11 of the frame as shown at 46 and serving to normally hold the members 38-39 in their inoperative position as shown in Fig. 1.

The bottom 14 of the frame is provided adjacent to the end wall 12 with an upwardly directed tubular rack guide 47 in which a rack 48 is vertically movable. The teeth 49 of the rack operate in connection with the pinion 19 on the gear 18 whereby the movement of the rack will rotate said gear 18, the shaft 17, and the gear 20 as well as the pinions 24 and 30. The rack 48 extends through the bottom 14 of the frame and is provided with a finger piece 50 whereby the same may be manipulated. Secured centrally of the inner face of the rack 48 is an inwardly directed yoke 51, the inwardly directed fingers 52 of which are adapted to operate in connection with the arms 42 of the members 38-39 to move said members together against the tension of the springs 45, as is illustrated in Fig. 5 of the drawing. This result is accomplished in the upward movement of the rack 48 and in the downward movement of said rack, the springs 45 automatically return the members 38-39 to their inoperative position. The rack guide 47 is slotted on its inner face as shown at 53 to permit of the passage of the shank of the yoke 51 therethrough.

The operation of my improved thread splicing machine will be readily understood from the foregoing description when taken in connection with the accompanying drawing and the following statement. With the parts in their inoperative position, as shown in Figs. 1 to 4 inclusive, the separate end portions of the threads 27-33 are secured

in the thread holding members 21 and 23 and to the end walls 12 and 13 of the frame in the manner hereinbefore described and as illustrated in Fig. 3, after which the rack 48 is grasped by one hand of the operator, it being apparent that the frame 10 is held by grasping the handle member 16 with the other hand, and said rack is moved upwardly in which operation the gears 18 and 20 are rotated comparatively fast, as are also the members 21 and 22 and the end portions of the separate threads 27 and 33 between the end walls 12 and 13 of the frame are unwound to bring the separate strands of the threads into their original or uncombined state. At the termination of the upward movement of the rack 48, the brushes 41 of the members 38-39 will be brought into the position shown in Fig. 5 to hold the unwound portions of the threads 27-33 together, after which the free ends of said threads are detached or broken off where they connect with the end walls 12 and 13 of the frame and the rack 48 is then moved downwardly, in which operation the twist originally taken out of said threads by unwinding the same is again replaced therein by reversing the rotation of the members 21 and 22 and the result of the completion of the downward movement of the rack 48 will be somewhat similar to that diagrammatically illustrated in Fig. 6. In Fig. 6 the thread 27 is indicated in solid black, while the thread 33 is indicated in white, and it will be apparent that the separate black and white threads 27 and 33 are twisted together.

By first dissecting the separate strands of the thread in the upward movement of the rack 48, as above set out, and then bringing the dissected end portions of two threads together and again twisting or rewinding the dissected strands of the thread, the strands are interlocked one with another in such manner as to reinforce and strengthen the spliced thread where connected. In other words, a thread spliced in the manner herein set out will be stronger at the point of splicing than at any other point along the thread. The chief feature of my invention is, in the fact, that by splicing the ends of a thread together in the manner set out the sizes or transverse dimensions of the thread is not materially increased and the present method of knotting or joining the threads by knotting, which is undesirable in manufacturing fabrics, garments or parts of garments is eliminated.

It will be apparent that while I have illustrated the use of brushes 41 for holding the dissected strands of the thread when unwound together prior to the rewinding of the same, other means may be employed for accomplishing this result, and various changes in and modifications of the details

of construction herein shown and described may be made, within the scope of the appended claims, without departing from the spirit of my invention or sacrificing its advantages.

Having fully described my invention, what I claim as new and desire to secure by Letters Patent, is:—

1. A machine of the class described comprising a frame, thread holding members rotatably mounted in said frame, means whereby the end portions of separate threads may be secured in said members, means for securing the free ends of said threads to said frame, and means for rotating said thread holding members in opposite directions to unwind and rewind the end portions of said threads to splice the same.
2. A machine of the class described comprising a frame, thread holding members rotatably mounted in said frame, means whereby the end portions of the separate threads may be secured in said members, means for securing the free ends of said threads to said frame, means for rotating said thread holding members in opposite directions to unwind the end portions of said threads, and means in said frame for holding the unwound end portions of said threads together.
3. A machine of the class described comprising a frame, thread holding members rotatably mounted in said frame, means whereby the end portions of the separate threads may be secured in said members, means for securing the free ends of said threads to said frame, means for rotating said thread holding members in one direction to unwind the end portions of said threads, means movably mounted in said frame for holding the unwound end portions of said threads together, and means for rewinding the end portions of said threads together by reversing the rotation of said members.
4. A machine of the class described comprising a frame, thread holding members rotatably mounted in said frame, means whereby the end portions of the separate threads may be secured in said members, means for securing the free ends of said threads to said frame, means for rotating said thread holding members in opposite directions to unwind the end portions of said threads, means in said frame for holding the unwound end portions of said threads together, means for rewinding the end portions of said threads together by reversing the rotation of said members, and means for moving said thread holding means out of engagement with the end portions of the threads in the operation of rewinding the same.
5. A machine of the class described comprising a frame, a shaft rotatably mounted therein; gears mounted on the opposite ends of said shaft, thread holding members mounted in the frame and geared in connection with said first named gears in such manner as to rotate in opposite directions, means for securing the end portions of separate threads in said members, means for securing the ends of said threads to the frame, and a rack movably mounted in the frame and adapted in one movement thereof to rotate said members in opposite directions to unwind the end portions of said threads.
6. A machine of the class described comprising a frame, a shaft rotatably mounted therein, gears mounted on the opposite ends of said shaft, thread holding members mounted in the frame and geared in connection with said first named gears in such manner as to rotate in opposite directions, means for securing the end portions of separate threads in said members, means for securing the ends of said threads to the frame, a rack movably mounted in the frame and adapted in one movement thereof to rotate said members in opposite directions to unwind the end portions of said threads, and means operated through said rack for holding the unwound end portions of said threads together.
7. A machine of the class described comprising a frame, a shaft rotatably mounted therein, gears mounted on the opposite ends of said shaft, thread holding members mounted in the frame and geared in connection with said first named gears in such manner as to rotate in opposite directions, means for securing the end portions of separate threads in said members, means for securing the ends of said threads to the frame, a rack movably mounted in the frame and adapted in one movement thereof to rotate said members in opposite directions to unwind the end portions of said threads, means operated through said rack for holding the unwound end portions of said threads together, and means whereby the movement of said rack in the opposite direction will release said thread holding means and reverse the rotation of said members to rewind and splice the end portions of said threads.
8. In a machine for splicing threads and the like, a frame, thread holding members mounted in said frame, means for operating said members in opposite directions to wind and rewind the end portions of two threads mounted therein and splice the same, and means movably mounted in said frame for holding the separate end portions of the thread together when unwound.
9. In a machine for splicing threads and the like, a frame, thread holding members mounted in said frame, means for operating said members in opposite directions to wind

and rewind the end portions of two threads mounted therein and splice the same, means movably mounted in said frame for holding the separate end portions of the thread together when unwound, and means whereby the operation of said first named means will operate said last named means.

In testimony that I claim the foregoing

as my invention I have signed my name in presence of the subscribing witnesses this 10 6th day of December, 1919.

HENRY A. LEMAY.
